BALL RACK CARRIER FOR POOL TABLES

Jacob Kremski, Pine Hall Farm, 10440 S. State Road,
Goodrich, Mich. 48438

Filed Mar. 14, 1975, Ser. No. 558,364

Term of patent 14 years

Int. Cl. D21

U.S. Cl. D34—3

FIG. 1.

FIG. 2.

FIG. 4.

FIG. 3.

FIG. 5.

FIG. 1 is a perspective view of a ball rack carrier for pool tables showing my new design;

FIG. 2 is a side elevation thereof, the other side being identical but reversed;

FIG. 3 is a top plan view;

FIG. 4 is a bottom plan view; and

FIG. 5 is a front elevation.

I claim:

The ornamental design for a ball rack carrier for pool tables, substantially as shown.
